(57) **CLAIM**

The ornamental design for an autonomous water vessel, as shown and described.

DESCRIPTION

FIG. 1 is a perspective view of an autonomous water vessel according to the first embodiment;

FIG. 2 is a front view thereof;

FIG. 3 is a back view thereof;

FIG. 4 is a first side view thereof;

FIG. 5 is a second side view thereof;

FIG. 6 is a top view thereof;

FIG. 7 is a bottom view thereof;

FIG. 8 is a perspective view of an autonomous water vessel according to the second embodiment;

FIG. 9 is a front view thereof;

FIG. 10 is a back view thereof;

FIG. 11 is a first side view thereof;

FIG. 12 is a second side view thereof;

FIG. 13 is a top view thereof; and,

FIG. 14 is a bottom view thereof.

The broken lines in FIGS. 1-3 and 6-14 indicate portions of the autonomous water vessel that do not form part of the claimed design.
